UNITED STATES PATENT OFFICE.

MARTIN T. A. KELLY, OF JOLIET, ILLINOIS.

WINDOW LOCK.

1,416,035.

Specification of Letters Patent. Patented May 16, 1922.

Application filed November 8, 1919. Serial No. 336,583.

To all whom it may concern:

Be it known that I, MARTIN T. A. KELLY, a citizen of the United States, residing at Joliet, in the county of Will and State of Illinois, have invented certain new and useful Improvements in Window Locks, of which the following is a specification.

This invention relates to window fasteners, and the primary object of the invention 10 is to provide an approved means for locking window sashes, when the same are in a semi-raised position for ventilation or the like, so that the window cannot be opened further by unauthorized persons on the outside of the 15 window.

Another object of the invention is the provision of an improved device carried by one of the window sashes and adapted to engage the other window sash to lock the window 20 sashes against opening movement toward each other.

A further object of the invention is the provision of an improved sash fastener carried by one of the window sashes and adapted 25 to normally lie out of the path of the other window sash and capable of extending outwardly in the path of the other window sash to prevent inward movement of the sashes.

30 A still further object of the invention is the provision of improved means for holding the sash fastener in an extended position in the path of a window sash, so as to prevent accidental displacement of the fastener.

35 A still further object of the invention is the provision of an improved window fastener embodying a locking pin arranged to engage the parts of the window fastener to hold the same in an operative position, the 40 fastener having means for receiving the pin to hold the same against loss, when the fastener is in an inoperative position.

A still further object of the invention is to provide an improved window fastener as 45 above referred to, which is durable and efficient in use, one which is simple and easy to manufacture, and one which can be placed upon the market at a reasonable cost.

Other objects of the invention will appear 50 in the following detailed description taken in connection with the accompanying drawings, forming a part of this specification, and in which drawings;

55 Figure 1 is a detail fragmentary sectional view of a window casing showing the invention applied thereto.

Figure 2 is an enlarged side elevation of the improved window fastener, showing the same applied to a window sash and in operative position.

Figure 3 is a plan view of the window fastener showing the same attached to a window sash and in inoperative position.

Referring to the drawings, wherein similar reference characters designate corresponding parts, throughout the several views, the letter A indicates a window frame of the ordinary or any preferred construction, having upper and lower sashes B and C slidably mounted therein; and D indicates the improved fastener.

The improved window fastener D includes the wings 5 and 6 which are preferably formed from metal plates either cast or rolled, and having the meeting ends thereof turned back to provide aligned hinge barrels 7 and 8 for the reception of a hinge pin or pintle 9.

The wing 6 is provided with a plurality of 80 equidistantly spaced apertures 10 for the reception of screws or other suitable fastening elements 11, by means of which the wing is secured to the side rail 12 of the upper sash B. The wing 16 is secured to the side rail 12 in spaced relation to the mid rail 13 of the upper sash B, so as to permit of a limited opening of the sashes in relation to each other.

The movable wing 5 is adapted to extend 90 outwardly and in the path of the lower sash B and in direct alignment with the wing 6, and the movable wing 5 is adapted to engage the upper rail 14 of the lower sash, as is clearly shown in Figures 1 and 2 of the drawings.

The movable wing 5 is held in extended position in direct alignment with the movable wing 6 by means of a removable pin 15 which is adapted to engage in eyes 16 and 17 formed on the upper terminals of the wings. 100 The upper terminals of the wings are rolled back upon themselves to form these eyes. The pin 15 is provided with a head 19 at one end thereof, so as to limit the inward movement of the pin when the same is placed in the eyes 16 and 17.

The outer free longitudinal edge of the wing 5 is rolled to provide a socket 20 for the reception of the locking pin, when the movable wing 5 is in its inoperative position 110 in abutting relation to the stationary wing 6.

In operation of the improved device, the

movable wing 5 is moved out of engagement with the stationary wing 6 until the same comes in direct alignment therewith which aligns the eyes 16 and 17. When the eyes 16 and 17 are in registration with each other the pin 15 is removed from the socket 20 and placed in the eyes which prevents swinging movement of the wing 5 on the hinge pin which holds the same in operative position in engagement with the upper rail. This prevents movement of the sashes toward each other and thus prevents anyone from gaining access to a room through a window provided with the improved lock. It can be seen that, when the hinged plate 5 is swung in inoperative position in abutting engagement with the immovable plate or wing 6, the same lies out of the path of the lower window sashes and permits the sashes to be readily raised and lowered.

By providing locks of this character, the window can be either lowered from the top and locked against further movement, or raised from the bottom and locked, or opened at the top and bottom and locked.

In practice, I have found that the form of my invention illustrated in the accompanying drawings, and referred to in the above description as the preferred embodiments, is the most efficient and practical, yet realizing conditions concurrent with the adoption of my device will necessarily vary, I desire to emphasize the fact that minor changes in details of construction, propor-

tion and arrangement of parts may be resorted to as desired, without sacrificing any of the advantages of my invention as set forth.

What is claimed as new is:

1. The combination with sliding sashes including side and end rails, of a fastener therefor including a stationary wing, means to secure the stationary wing to one of the side rails of one of the sashes in spaced relation to the end rails thereof, a movable wing hingedly secured to the outer end of the stationary wing adapted to extend in direct alignment with the stationary wing and in the path of the lower sash for engaging the upper end rail thereof, eyes formed on the upper ends of the wings and a removable pin arranged to fit in said eyes when the wings are in aligned position.

2. A window sash fastener comprising a pair of hingedly connected wings, eyes formed on the upper terminals of the wings and adapted to be brought into registration with each other when the wings are in their extended positions, and a pin adapted to fit in said eyes when the wings are in their extended positions.

3. In a window sash fastener, a pair of hingedly connected sections, a pin for holding the sections against swinging movement, and a socket carried by one of said wings for the reception of said pin.

MARTIN T. A. KELLY.
